(57) **CLAIM**

The ornamental design for a bottle, as shown and described.

DESCRIPTION

FIG. 1 is a top plan view of a bottle showing our new design;

FIG. 2 is a front elevational view thereof;

FIG. 3 is a right side elevational view thereof;

FIG. 4 is a rear elevational view thereof; and,

FIG. 5 is a left side elevational view thereof.

The oblique shade lines shown in the drawings represent that the bottle is transparent.

The broken lines showing environment are for illustrative purposes only and form no part of the claimed design.
